REGULATOR CONTROLLED BY ELECTRON
TUBE

Seth August Holmqvist, Appelviken, Sweden, assignor to Telefonaktiebolaget L. M. Ericsson, Stockholm, Sweden, a company of Sweden

Application November 24, 1947, Serial No. 787,767
In Sweden December 3, 1946

4 Claims. (Cl. 236—78)

1

It is important to incorporate safety devices in all apparatus controlled by regulators, in order to protect the apparatus in case any of the parts thereof should become inoperative. As an example we can mention a regulator for keeping the temperature in an oven constant. The temperature-sensitive member, i. e. the transmitter in such a regulator, is always subjected to great stresses, and when some defect occurs in said member, the heating element of the oven should be turned off to prevent the temperature from damaging the oven or its contents. In electron tube controlled regulators, such safety devices are known, in which the heating element of the oven is automatically turned off upon the occurrence of certain defects in the temperature sensitive member, e. g. open circuiting thereof. Said devices have the disadvantage, that the heating element of the oven is not turned off on the occurrence of a short-circuit in the temperature-sensitive member. The present invention has for an object the elimination of such disadvantage and to provide a safety device for use with electron tube controlled regulators, which device is operative for short-circuits in the transmitter as well as for other defects.

The invention will be described more in detail with reference to the accompanying drawing, in which Fig. 1 is a circuit diagram showing the principle for a known form of simple vacuum tube regulator for keeping the temperature in an oven constant, and Fig. 2 is a similar diagram of a regulator of the same type designed according to the invention.

The two circuits shown in Figs. 1 and 2 operate according to the following fundamental principle. The heating element E of the oven u is turned on by a relay A having a contact K. Relay A is disposed in the anode circuit of an amplifying tube II. The anode current in said tube and therefore relay A is controlled from a temperature-sensing transmitter R6 disposed in the oven and having the form of a resistance, in connection with an amplifying tube I. When the anode current in the amplifying tube II increases to a certain value, the heating element E is turned on by relay A, and when the anode current decreases below a certain value, the current supply to the heating element E is turned off by said relay.

To begin with, the known circuit shown in Fig. 1 will now be described in detail. From the secondary winding S3 of a transformer T, the primary winding P of which is supposed to be connected to a source of alternating current, current is supplied to a bridge circuit comprising

2

a fixed resistance R5, a potentiometer R4 and the temperature-sensitive resistance R6 arranged in the oven u. The oven is heated by means of the heating element E. c is a sliding contact which is adjustable along the potentiometer R4. The voltage fed to the grid of the tube I, which voltage is obtained from the sliding contact c, is determined by the position of said contact and by the relation between the resistances R5 and R6. 5 The anode voltage for the tube I, which is provided with an anode resistance R1, is supplied from the winding S1 on the transformer T, which voltage is rectified by the rectifier L and the voltage thus obtained is filtered in a way known per se by means of a filtering circuit containing the condensers C1 and C2, the resistance R2 and the lead L1. The anode circuit of the amplifying tube II is fed from the winding S1 through the relay-winding A. The alternating current amplified by the tube I is supplied to the grid of the tube II through the coupling condenser C3. Said grid is also fed from the secondary winding S2 of the transformer T through the grid resistance R3, with a voltage which is chosen so that the 10 anode current in the tube II is so low that the armature of the relay A is released when no voltage has been supplied to the grid of the tube II from tube I over the condenser C3. Since the anode circuit of the tube II is fed with current 15 by the tube I, the anode current in the tube II will be dependent on the phase relation between the voltages on the grid and the anode of the tube II. During those half cycles 20 in the alternating current when the anode is negative (relatively to the cathode) the anode current is always zero. During the positive half cycles, the magnitude of the current is dependent upon the grid voltage. If this latter is positive 25 (the same phase position) anode current will appear, and if it is negative, the anode current will remain zero also during said positive half cycle.

If the resistance values in resistances R5 and R6 are equal and contact c occupies a position in 30 the middle of the resistance R4 ($a=b$), the voltage feeding the grid of the tube I is zero, and the grid voltage on tube II is thereby determined only by the voltage of the secondary winding S2. The anode current in the tube II is thus zero, and relay A is released. If the temperature in the 35 oven now decreases, the resistance value of resistance R6 decreases, the balance of the bridge circuit is disturbed and an alternating voltage is supplied to the grid of tube I. Said voltage is 40 amplified and fed to the grid of tube II. The 45 relay A is then again turned on. If the temperature in the oven now increases, the resistance value of resistance R6 increases, the balance of the bridge circuit is disturbed and an alternating voltage is 50 supplied to the grid of tube I. Said voltage is 55 amplified and fed to the grid of tube II. The

phase relation is chosen so that during the half cycle when the voltage on the anode is positive, the grid is also positive. Anode current therefore appears, and relay A turns on the oven heating element E. The temperature now increases in the oven, the resistance of the transmitter R6 thereby increasing and the balance in the bridge circuit being re-established, whereby the grid voltage on tube I becomes zero and relay A again turns off the heating element E. Should the temperature increase above the value to which the temperature has been set beforehand, the resistance of the transmitter R6 will increase and the balance in the bridge circuit will be disturbed again, the grid in tube I then being fed with a voltage which is 180° out of phase relatively to the voltage which is fed thereto when the temperature is too low in the oven. This entails that the grid in tube II is fed with a voltage which is 180° out of phase relatively to the anode voltage, due to which the anode current will remain zero even during the positive half cycles of voltage applied to the anode in tube II. The armature of the relay A therefore remains released and the heating element E is not turned on. The desired temperature in the oven can be set beforehand to a suitable value by adjusting the contact c on the potentiometer R4.

A great advantage with the above described prior art regulator is that if some of the delicate parts should become inoperative, the heating element of the oven is turned off. This is true for instance as regards both the electron tubes, the rectifier L and the transformer T. The most delicate part of the regulator is however the transmitter R6. An open circuit condition in said transmitter corresponds to an infinitely high temperature in the oven, due to which relay A turns off the oven heating element E. A short-circuit in the transmitter R6 or in its connecting leads, on the other hand, corresponds to a low oven temperature, due to which relay A remains energized and the oven element E remains turned on, independent of the temperature of the oven.

This disadvantage is eliminated by means of the arrangement shown in Fig. 2, in which, according to the invention, the rectifier for the anode circuit of tube I consists of a grid controlled rectifying tube III, suitably a gas-filled thyratron tube, the anode of which is connected to one of the terminals of the transformer winding S1, and the heating current of which is supplied from the winding S4 on the transformer T. Such a tube has the characteristic, that at a certain negative grid voltage it works as a normal rectifier. If, on the other hand, the negative grid voltage increases up to a certain value, the tube ceases to glow. In the circuit shown in Fig. 2, the extinction of tube III entails that the anode voltage for tube I ceases. Tube II thus ceases to function and relay A breaks the current supply to the heating element E. If tube III can thus be extinguished when the transmitter R6 becomes short-circuited, safety is obtained in that the oven element E will be turned off upon such a short-circuit, and the condition for this will thus be, that the negative grid voltage of tube III becomes sufficiently high upon occurrence of a short-circuit in the transmitter. This can be accomplished by supplying said grid from a winding S4 on transformer T with a voltage which, by means of the potentiometer R7, is set to such a value that the grid, merely because of said voltage, receives a negative voltage having such a magnitude that the tube III is blocked

during that half cycle in which the anode is positive. The voltage drop across the resistance R6 is therefore applied over the line L2 and the transformer T1 to the grid of tube III. The grid voltage on tube III is thus determined by the voltages from T1 and S4 and the circuit is arranged so that the voltage from T1 and the blocking voltage from S4 are out of phase by an angle 180°, on account of which the blocking voltage from S4 is counteracted by the voltage originated at R6. The magnitudes of said two voltages are chosen so that their resultant in normal cases has such a value that during the half cycle when the anode is positive, the tube is not blocked, due to which tube III thus as in normal cases operates as a rectifier. If the voltage drop across transmitter R6 now disappears due to the transmitter being short-circuited, the voltage on the grid in tube III will be determined exclusively by the voltage from winding S4, and tube III thereby, as mentioned above, will be blocked, which ensures that the anode circuit of tube I is broken, relay A thereby breaking the current supply to the oven heating element E over contact k.

By means of a regulator of the type just described, the oven temperature is thus prevented from exceeding the predetermined value even if the transmitter or its leads becomes inoperative from either short-circuit or open circuit conditions.

The invention can be modified in several different ways within the scope of the invention. For example, if the circuit comprises only one electron tube, the relay winding A and the rectifier tube III will be connected in series in the anode circuit of said tube.

I claim:

1. A regulating device for automatically maintaining the condition of a quantity at a predetermined value, comprising a resistance bridge, one arm of said bridge including a resistor whose resistance varies in accordance with the condition of said quantity, a source of alternating current connected across opposite input terminals of said bridge, a first and a second space discharge device each comprising at least an anode, a cathode and a control grid, said devices being connected in cascade with the cathode and control grid of the first device connected across opposite output terminals of said bridge, a relay comprising an operating coil and contacts controlled thereby, a circuit connecting said coil, said source and the anode-cathode path of the second device all in series relationship, means controlled by the condition of said contacts for varying the condition of said quantity, a grid-controlled rectifier tube energized from said source and connected to supply anode voltage to said first device, means for applying an alternating bias voltage from said source to the grid of said rectifier tube, a shunt circuit across said resistor for deriving an alternating voltage from current passing therethrough, and means for applying said alternating voltage to the grid of said rectifier tube in phase opposition to said bias voltage, said voltages being so adjusted that their conjoint effect upon said rectifier is insufficient to block conduction of the same until the voltage developed across said resistor drops below a predetermined minimum corresponding to a short circuit thereof.

2. The invention in accordance with claim 1, in which said rectifier includes a cathode, a circuit for deriving cathode-heating current from

said source, and in which the means for applying bias voltage to the grid of said tube comprises an adjustable potentiometer connected across said heating circuit.

3. The invention in accordance with claim 1, in which said resistor comprises thermally responsive material, and in which the means for varying the condition of said quantity comprises a heating element.

4. The invention in accordance with claim 1, in which said rectifier tube comprises a gas-filled thyratron tube.

SETH AUGUST HOLMQVIST.
